UNITED STATES PATENT OFFICE.

JASPER S. COXEY, OF ABERDEEN, WASHINGTON.

FOLDING AND EXTENSION CAR-STEP.

1,141,615.

Specification of Letters Patent.

Patented June 1, 1915.

Application filed June 23, 1914. Serial No. 846,833.

To all whom it may concern:

Be it known that I, JASPER S. COXEY, citizen of the United States, residing at Aberdeen, in the county of Chehalis and State of Washington, have invented certain new and useful Improvements in Folding and Extension Car-Steps, of which the following is a specification.

My invention relates to new and useful improvements in folding steps, and has particular reference to those known as the extensible type which are employed especially in connection with railway cars, street cars and the like.

The primary object of my invention is to provide an extensible step which may be pivotally connected to the fixed steps of a car and is equipped with operating mechanism whereby it may be easily, quickly and conveniently projected to extend beyond the fixed steps and below the same, or may be drawn inwardly to a position against the lower terminal of the fixed steps.

As is well-known, cars employed on suburban lines, as well as railway cars, are now constructed with rear platforms having not only an ordinary door, but also a drop door which constitutes a section of the platform floor and, when in closed position, forms a continuation of the platform floor and prevents the use of the steps.

A further object of my invention is, therefore, to provide for the platform of the car to which my extensible step is attached a side swinging gate and a drop door, and to operatively connect these two members with the mechanism which actuates the extensible step so that, by the manipulation of but a single lever, the gate and door may be moved into closed position and the step drawn up into folded position, or the gate and door may be opened simultaneously with the movement of the step into extended position.

A still further object is to provide for the extensible step, drop door and gate at each side of the car platform an operating mechanism which includes two independent units adapted at times to be operatively connected whereby, if desired, the extensible step may be held in folded position and the drop door and gate moved to open position.

A further object is to construct the door, gate and step operating mechanism with such regard to proportion, number and arrangement of parts that it may be cheaply manufactured, will be efficient and durable

in service, and may be readily applied to the platform of any car of standard construction with a minimum expenditure of time and labor.

The above recited and other incidental objects of a similar nature, which will be hereinafter more specifically treated, are accomplished by such means as are illustrated in the accompanying drawings, described in the following specification, and then more particularly pointed out in the claims, which are appended hereto and form a part of this application.

Referring now to the drawings, wherein there has been illustrated the preferred embodiment of this invention as it is reduced to practice, and throughout the several views of which similar reference numerals designate corresponding parts, Figure 1 is a perspective view of the rear platform of a railway car, showing a pair of extensible steps of my invention accompanied by the actuating mechanism which controls not only the steps but also the drop door and gate of the platform. At the right hand side of this figure the step is shown in extended position, and the gate and door of the platform are shown in open position, while at the left hand side of this figure the gate and door are in closed position and the step is in folded position; Fig. 2 is a side elevation of the rear end of a railway car, showing the side of the platform with the adjacent step in folded position; Fig. 3 is an enlarged detail view illustrating the post of the gate, the rod and collar which are employed in swinging this member from open to closed position, and vice-versa, and the lever which operatively connects this rod to the step actuating mechanism; Fig. 4 is an enlarged detail perspective view of a cover or casing which is employed in bad weather for protecting the steps and the controlling mechanism from sleet, snow, rain and the like; Fig. 5 is a detail view of the lever employed in connecting the gate operating rod to the hand operating lever; Fig. 6 is a detail perspective view of the gate operating rod and the block by which it is connected to the lever of Fig. 5; and Fig. 7 is a detail perspective view of the two hand levers, one of which controls the extensible step, and the other of which controls the gate and drop door.

In the embodiment of my invention shown in the accompanying drawings, the rear plat-

form 10 of the car is provided at each side with a drop door 11 and a gate 12. It may be well to explain at this point that the invention contemplates the substitution of a 5 regulation door for each gate 12 in case the mechanism is applied to a vestibuled platform.

As previously stated, the fixed steps of each side of the platform 10 are equipped 10 with extensible steps 13 which are controlled by the same controlling mechanism which moves the drop doors 11 and gates 12 from open to closed position, or vice-versa.

15 The drop doors 11 are, of course, hinged to the rear platform beam 14 by hinges, indicated at 16. The gates 12 are mounted on posts 17 which are journaled at the terminals of the beam 14 and are adapted to rotate for swinging the gates when actuated by the extensible step-controlling mechanism, as will be hereinafter more fully described.

Each auxiliary extensible step member 13 20 consists preferably of a rectangular board, although, if so desired, a metal step may be employed. Each step is mounted on a pair of supporting bars 18 which are swingingly connected to the lower terminals of the fixed 25 steps A by the links 19. A pair of these links 19 is provided for each of the bar members 18, being pivoted at their upper terminals between the apertured ears 20 carried by the fixed steps, and at their lower 30 terminals between similar ears 21 carried by the bars 18. It will thus be seen that the rear terminals of the step supporting bars are firmly connected to the lower terminals 35 of the fixed steps by parallel links. As a means for swinging these auxiliary step members 13 to either extend them, as at the right hand side of Fig. 1, or to fold them, as at the left hand side of Fig. 1, I provide an operating lever 22 which is pivoted intermediate its length on the clutch 40 plate 23 secured to the beam 14. The lever 22 carries a spring actuated locking pawl 24, which is engageable with the clutch plate 23 in the usual manner, and serves to hold the 45 lever in adjusted position. The lower terminal of each lever 22 extends for a considerable distance below the floor of the platform 10, and is pivotally connected by a link 25 and a crank arm 26 to a shaft 27, which 50 is terminally journaled at the elbows of a pair of L-shaped hangers. These hangers each includes a vertical arm 28 and a horizontal arm 29, the former of which is secured to the platform and the latter of 55 which is terminally secured to the fixed steps A by bolts 30, or similar fastening devices.

The crank arm 26 is, of course, keyed to the shaft 27, so that the swinging of the 60 lever 22 will act to rotate the shaft 27 in a

direction corresponding to the movement of the latter. In operatively connecting the shaft 27 to the auxiliary steps 13, I have provided a pair of pivotally connected link members 31 and 32. The outer terminals of 70 the link members 32 are pivotally connected, as at 33, to the rear terminal of the adjacent step supporting bar 18, while the inner terminal of each of the link members 31 is fixed on the shaft 27 for rotation therewith. 75 It is necessary, of course, to provide some means for limiting the swinging movement of the links 31 and 32 with respect to each other when the auxiliary steps 13 are moved into position, as at the right hand side of Fig. 1. For this purpose there is provided a laterally extending stop arm 34 which is formed on the upper edge of the member 32 at its rear terminal and is disposed to engage in a notch 35 formed in the upper edge 80 of the member 31 adjacent the pivoted terminal thereof. It will be seen upon reference to the right hand side of Fig. 1 that, when the step is in position the pivot pin 32', which connects the links 31 and 32, lies 90 below a line connecting the opposite terminals of the links, so that a weight supported by the step 13, as when a passenger is ascending to the platform, will not tend to swing the steps inwardly. 95

From the foregoing description, it will be seen that the lever 22 may be manipulated to extend the steps 13, or to pull them into folded position to meet the lower terminals of the fixed steps A. 100

In operatively connecting the levers 22 to the drop doors 11 of the platform and the gate members 12, so that these members may be opened or closed in the manner hereinbefore explained, I provide a disk member 105 36 and a link 37. The disk 36 is pivoted adjacent its upper edge to a bracket 38 which depends from the beam 14 of the platform. The disk is substantially heart-shaped, and is freely connected to a lever 22' by the link 110 39, one terminal of which is pivoted to the disk and the other terminal of which is pivoted to the lever. It is here to be noted that one of these levers 22' is employed in connection with each of the levers 22. The 115 members 22' are pivotally connected to the clutch plates 23 by the same pivot pins on which the members 22 are mounted. The levers 22' are of less length than the members 22, however, their lower terminals extending to such a point that they are approximately horizontally aligned with the disk members 36. As will be hereinafter more fully described, the levers 22' may be operated independently of the members 22 120 to swing the drop doors 11 upwardly and to open the gate members 12, while the steps 13 are retained in folded position by the levers 22. It is, of course, often desirable, however, to move the levers 22 and 22' simultaneously, 125 130

so that the gate and drop door will be opened simultaneously with the projection or retraction of the steps 13. For this purpose, I employ a latch, preferably of the type shown in detail in Fig. 5. This latch consists in a hook member *a*, which is attached to the upper terminal of the lever 22 by a bracket plate *b*. The bill of the hook is engageable in a groove *c* formed in the upper terminal of the lever 22'. When the bill of the hook is engaged properly in this groove *c* it is obvious that the two levers 22 and 22' will be locked and may be swung as an entirety.

10 On the inner face of the disk 36 is pivoted in any suitable manner a drop door operating rod 40, which is illustrated particularly in Fig. 2. The outer terminal of this operating rod 40 is pivoted on a pin 41 between the spaced apertured ears 42 which extend from the lower face of the platform drop door 11 and adjacent the hinged terminal thereof. It will thus be seen that the lever 22 may be swung to oscillate the disk 36 on its pivot to project the rod 40 upwardly, with the resultant upward swinging of the platform drop door 11 into open position, in the manner disclosed particularly at the right hand side of Fig. 1.

15 As a means for operatively connecting the disk 36 to the post 17 of the gate, I employ a lever 43 and a vertical operating rod 44. The lever 43 is pivoted intermediate its length to a depending bracket 45. This lever 43 and operating rod 44 are shown in detail in Fig. 3, and reference will now, therefore, be had to this figure. The lever 43 is, of course, formed from a length of bar metal, and is bifurcated at its inner terminal, as indicated at 46. This bifurcation 46 receives a pivot pin 47 carried by the heart-shaped disk member 36. The other terminal of the lever 43 is formed with a head 48 which is insertable in the horizontal transversely extending slot 49 formed in the block 50. This head member 48 is freely received within the slot 49 so that the swinging of the lever 43, in a manner which will be herein-after fully explained, will effect either the 20 raising or lowering of the block and the consequent upward or downward movement of the gate operating rod 44. The lower terminal of this rod 44, which is preferably square in cross-section, is received within a 25 square socket 51 extending inwardly into the block from the upper face thereof. A set screw 52 threaded through the side of the block is employed for adjustably holding the lower terminal of the rod 44 in attachment to the block.

20 On the upper terminal of the gate operating rod 44 is formed an annular collar 53, which is adapted to embrace the gate post 17 and is provided with an inwardly projecting lug 54. This lug 54 is arranged,

when the collar is positioned on the post 17, to extend into a serpentine slot which is formed in the post. In this connection it is desirable to explain that the post 17 is preferably formed from a metallic tube, although a solid post may be employed, if desired. The slot in which the lug 54 is arranged consists in a diagonally extending intermediate portion 55 and vertically extending terminal portions 56 and 57. The 75 terminal portions 56 and 57 of the slot are preferably located so that they are circumferentially spaced an approximate distance of ninety degrees. It will thus be seen that, if the collar 53 moves from a position at 80 the lower terminal of the post to a position adjacent the upper terminal thereof, the lug 54 in riding through the slot of the post will cause a ninety degree rotation of the post, thus swinging the gate from open to closed 85 position. It will also be apparent that, if the collar is arranged adjacent the upper terminal of the post, as when the gate is in open position, a downward pull on the rod 44 will move the lug 54 through the slot, 90 disposing it in the terminal portion 57 thereof with a consequent swinging of the gate into closed position. In order to permit the collar 53 to move freely throughout the major length of the post 17, I have spaced 95 the inner vertical rod 59 of the gate from the post, as in Fig. 3, by connecting it to the upper and lower horizontal bar members 59 and 59' and connecting the terminals of these members to the post.

100 It will now be apparent that the lever 22 of either auxiliary step may be swung inwardly toward the center of the car platform to simultaneously extend the step 13, swing the drop door 11 upwardly, and swing the gate inwardly into folded position against the rail of the platform. It will also be observed that, by releasing the hook member *a* from engagement with the lever 22', this latter member may be employed 110 independently of the lever 22 for opening or closing the gate and drop door while the step 13 is retained in folded position.

115 It has been found in practice that the various portions of the operating mechanism, being constructed as they are from metal, are liable to become rusty and, consequently, damaged in case the car is held in a yard for a considerable length of time during bad weather, and for this reason I have provided 120 a protecting casing or housing which is illustrated particularly in Fig. 4. This housing consists in a rear wall 60, a pair of side walls 61 and 62, and a bottom wall 63. The rear wall 60 is provided with a vertically extending elongated slot 64 which receives the link 25 so that the vertical arms 28 of the hanger brackets which support the shaft 28 may be engaged by the rear wall. Slots, indicated at 64' are also formed in 130

the side walls 61 and 62 for the reception of the shafts 27. The casing is, of course, open at one terminal so that it may be freely applied to bring the terminals of the side walls 61 and 62 into engagement with the side boards of the fixed steps A.

As a means for attaching the casing to the platform, I provide in the side walls the laterally extending apertured ears 65 10 and 66, and for the rear walls 60 similar members 67 and 68 which are located on opposite sides of the slot 64. On the upper edges of these side walls and on the terminal edges thereof are formed the terminally extending flanges, indicated at 69 and 70. Extending outwardly from the flanges 70 are the apertured ears 71 and 72, which are adapted to be secured by bolts or similar fastening devices to the side boards of the 20 fixed steps A. One of these casings or shields is, of course, provided for each side of each pair of steps so that the link members and associated mechanism at each side of each step may be adequately housed. 25 Thus it will be seen that, when the car is not in use, the operating mechanism for the steps, gate and door may be completely housed by the casing and guarded against rains, snow, sleet and the like.

30 In many instances it is desirable to operate the extensible steps, gates and drop doors mechanically instead of utilizing the manually operable levers 22 and 22'. For this purpose, therefore, I connect each lever 35 22 to a compressed air cylinder 73. These compressed air cylinders 73 may be of standard construction and are suspended from the platform of the car by hanger brackets 74. In each cylinder is contained a 40 piston head 75 which is connected to the adjacent lever 22 by a pitman rod 76. Surrounding the rod 76 is a helical spring 77. One terminal of the spring bears against the piston head 75 and the other terminal 45 bears against the end closure wall 78 of the cylinder. This spring normally tends to hold the piston head at the inner end of the cylinder, so that the steps are normally held in folded position. It will be obvious, however, that, if compressed air is let into the 50 inner end of the cylinder 73 through the pipe 79, the piston head 75 will be forced outwardly against the tension of the spring, thus swinging the lever 22 through the medium of the member 76 to such position that the step 13 will be extended.

In reduction to practice, it has been found that the form of this invention illustrated in the drawings, and referred to in the 60 above description as the preferred embodiment, is the most efficient and practical; yet realizing that the conditions concurrent with the adoption of this device will necessarily vary, it is desirable to emphasize the fact

that various minor changes in details of construction, proportion and arrangement of parts may be resorted to, when required, without sacrificing any of the advantages of this invention, as defined in the appended claims.

Having thus described my invention, what I claim is:

1. The combination with a car platform, of a gate, a drop door, an extensible auxiliary step, an operating lever controlling the auxiliary step, a second operating lever independent of the first-mentioned lever and controlling the gate and door, a pneumatic device operatively connected to the first-mentioned lever, and means whereby the first and second-mentioned levers may be operatively connected for consonantly effecting the extending of the steps and opening of the gate and door or folding of the steps and closing of the gate and door. 85

2. The combination with a car platform, of a gate mounted for horizontal swinging movement, a drop door mounted for horizontal swinging movement, an extensible pivotally mounted step, an operating lever controlling the step, a second lever independent of the first-mentioned lever for controlling the gate and door, a pivoted disk member, a link connecting the disk to the second-mentioned lever, a rod pivotally connecting the door and disk whereby the swinging of the disk in one direction will open the door and the swinging of the disk in the other direction will close the door, a vertically movable member connected to the gate and adapted upon downward movement to open the gate and upon upward movement to close the gate, and a link pivoted intermediate its length to the car platform and terminally connected to said vertically movable member and to the disk for operatively connecting the gate to the second-mentioned lever. 95

3. The combination with a car platform, of a gate mounted for horizontal swinging movement, a door mounted for vertical swinging movement, a pivotally mounted extensible step, a lever pivoted to the car platform and controlling the extensible step, a second lever pivoted to the car platform and operatively connected to both the gate and door for controlling the opening and closing of the gate and door, said first and second mentioned levers being independently operable, a pneumatic device operatively connected to the first-mentioned lever for controlling the movement of the same, and a hook member carried by one of the levers and engageable with the other lever whereby the levers may be operatively connected, said levers when operatively connected being adapted to be actuated by the pneumatic device for simultaneously ex- 110
115
120
125

tending the extensible step and opening the gate and door, or to simultaneously fold the step and close the gate and door.

4. The combination with the platform of a car, of a gate including a body portion and a post, said post being journaled for rotation in a vertical plane and being provided in its face with a serpentine groove, and means for swinging the gate, said 10 means including an operating lever pivoted in the platform, a disk pivotally attached to the platform, a link freely connecting the disk and lever, a vertically movable rod, a collar carried by the upper terminal of the 15 rod, said collar surrounding the post and being slidable thereon, a lug extending radially from the inner face of the collar, said lug being disposed within the said groove and being adapted for movement 20 therethrough to rotate the post, and a lever connecting the operating rod and disk whereby the operating lever may be swung

to move the operating rod in a vertical plane.

5. The combination with a car platform, 25 of a gate and an operating mechanism therefor, said gate including a body portion, and a vertically disposed rotatably mounted post having a serpentine facial groove, said operating mechanism including an operating lever, a collar embracing the post and slidable vertically thereon, a lug formed integrally with the collar and disposed for movement through the groove in the post, and means operatively connecting the collar 30 and lever whereby the lever may be swung to slide the collar vertically on the post.

In testimony whereof I affix my signature in presence of two witnesses.
